UNITED STATES PATENT OFFICE.

LEWIS C. PARKER AND FREDRICK W. BUSSMEYER, OF ST. LOUIS, MISSOURI.

GAS-PRODUCER.

No. 924,819.

Specification of Letters Patent.

Patented June 15, 1909.

Application filed July 2, 1908. Serial No. 441,634.

To all whom it may concern:

Be it known that we, LEWIS C. PARKER and FREDRICK W. BUSSMEYER, citizens of the United States, residing at St. Louis, in the State of Missouri, have invented certain new and useful Improvements in Gas-Producers; and we do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in gas producers and the object in view is to produce an apparatus of this nature in which the grate bars will present a large area of combustion surface, the bars being separate and adapted to be interchanged.

20 The invention comprises various details of construction, combinations and arrangements of parts which will be hereinafter 25 fully described and then specifically defined in the appended claims.

We illustrate our invention in the accompanying drawings, in which:—We have shown a sectional view of gas producer, 30 showing features of our invention.

Reference now being had to the details of the drawings by letter, A designates a vertical tubular shell of the producer having a refractory lining B.

35 Mounted near the lower part of the tubular shell is a casting F having a central opening F' and said casting has an annular groove F² in which the upper angled ends G' of the grate bars G are adapted to be held. Bars H are pivotally connected at 40 their upper ends to said casting and at their lower ends to an annular ring I at I' and a shoulder I² upon said ring forms means for supporting the lower ends of the grate bars.

45 The upper end of each bar H projects into a recess in the under surface of said casing. Said ring I has a second shoulder I³ upon which a sliding grate J is mounted, which latter is provided with a suitable handle J'

50 and guide extensions J² are provided upon which the grate is adapted to rest as it is reciprocated. A blower K is mounted upon the outer wall of the producer and a pipe K'

leads therefrom to the space below the grate. An ash trap L leads from the lower portion 55 of the producer through which ashes are adapted to fall into the pit L'. A pipe Q² leads through the wall of the producer and opens at its lower end underneath the gas 60 through which air is adapted to be introduced.

At suitable distances above the grate capped openings S are provided in the walls of the gas producer through which the fire may be observed and the material may be 65 agitated by pokers.

What we claim to be new is:—

1. In combination with the wall of a gas producer, a casting fastened to said wall and provided with a central opening, the marginal edge of which is provided with an annular groove, a series of grate bars, the upper ends of which are angled and rest upon the projecting bottom wall of said groove, a ring, links pivotally connecting the same 70 to said casting and upon which the lower ends of said grate bars rest, said ring having an annular shoulder upon the inner periphery thereof, and a grate resting upon said shoulder of the ring, as set forth. 75

2. In combination with the wall of a gas producer, a casting fastened to said wall and provided with a central opening, the marginal edge of which is provided with an annular groove, a series of grate bars, the 85 upper ends of which are angled and rest upon the projecting bottom wall of said groove, a ring having shouldered portions upon the inner marginal edge thereof, the lower end of said grate bars resting upon 90 one of said shoulders, links pivoted at their upper end in grooves formed upon the under surface of said casting, their lower ends pivoted to said ring above the lower ends of the grate bars, a grate mounted upon said 95 ring and resting upon the lower of said shoulders, as set forth.

In testimony whereof we hereunto affix our signatures in the presence of two witnesses.

LEWIS C. PARKER.
FREDRICK W. BUSSMEYER.
